US00D870789S

(12) **United States Design Patent** (10) Patent No.: **US D870,789 S**
Blanchard et al. (45) Date of Patent: **** Dec. 24, 2019**

(54) **SUNGGLASSES**

(71) Applicant: **100% SPEEDLAB, LLC**, San Diego, CA (US)

(72) Inventors: **Marc Blanchard**, Solano Beach, CA (US); **Ludovic Boinnard**, San Diego, CA (US)

(73) Assignee: **100% Speedlab, LLC**, San Diego, CA (US)

(**) Term: **15 Years**

(21) Appl. No.: **29/672,927**

(22) Filed: **Dec. 10, 2018**

Related U.S. Application Data

(63) Continuation of application No. 29/605,269, filed on May 24, 2017, now Pat. No. Des. 855,096, which is a continuation of application No. 14/548,217, filed on Nov. 19, 2014, which is a continuation-in-part of application No. 29/501,895, filed on Sep. 9, 2014, now Pat. No. Des. 727,400, and a continuation-in-part of application No. 13/750,093, filed on Jan. 25, 2013.

CLAIM

The ornamental design for sunglasses, as shown and described.

DESCRIPTION

FIG. 1 is a front perspective view of sunglasses showing our new design;

FIG. 2 is a rear perspective view thereof;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the drawings illustrate environmental features and form no part of the claimed design.
